UNITED STATES PATENT OFFICE

LAWRENCE C. BURKS AND JOHN A. BUCHHEIT, OF UNIONTOWN, PENNSYLVANIA

PROTECTOR FOR MINING TOOLS

Application filed February 25, 1927. Serial No. 171,047.

This invention relates to a protection device designed primarily for use to prevent theft of the various tools employed by a miner although it is to be understood that the device can be used for holding other articles.

One of the objects is to provide a device of this character which will hold a group of tools assembled so that, after the device has been properly locked it becomes impossible 10 to separate the tools.

It frequently happens among miners and others using various tools in their labors, that some of the tools are stolen or lost when laid aside unused and it is an object of the present 15 invention to provide a means whereby the tools, when not in use, can all be grouped together and securely fastened, thereby to practically obviate all danger of theft or loss of any of the tools.

20 A further object is to provide a device of this character which is simple, durable and compact in construction, and which, when assembled with the tools, will permit of all of the tools being carried at one time in a convenient way.

With the foregoing and other objects in view which will appear as the description proceeds, the invention resides in the combination and arrangement of parts, and in 30 the details of construction hereinafter described and claimed, it being understood that changes in the precise embodiment of the invention herein disclosed may be made within the scope of what is claimed, without departing 35 from the spirit of the invention.

In the accompanying drawings the preferred form of the invention has been shown.

In said drawings,

40 Figure 1 is a side elevation of the device, a set of mining tools being shown assembled therewith.

Figure 2 is a top plan view of the structure shown in Figure 1.

45 Figure 3 is a top plan view of the protecting device on an enlarged scale.

Figure 4 is a side elevation thereof.

Figure 5 is an end elevation.

50 Referring to the figures by characters of reference 1 designates an elongated frame formed preferably of a light metal rod bent

to provide a contracted portion or tongue 2 at one end of the frame, it being understood that the rod constituting this frame and tongue is continuous and unbroken. The free end portion of the tongue 2 has an opening 3 extending therethrough while mounted on that end of the frame 1 remote from the tongue 2 are one or more sleeves or eyes 4 provided at the free ends of arms 5. These arms diverge from an inverted yoke 6 having a long side formed partly of the arms 5 and a short side. A retaining arm 7 is integral with the short side of the yoke and has a finger 8 at one end merging into an ear or lug 9 provided with an opening 10. This opening is designed to register with the opening 3 when the lug 9 is in contact with the tongue and, with the parts thus located, the finger 8 will support the strip 7 substantially parallel with the plane occupied by the frame 8 and tongue 2. At a point substantially in line with the short side of the yoke 6 a cross bar 11 is provided in the frame 1, this bar being formed integral with the sides of the frame as shown.

55 In using this device those tools of the hammer type are mounted on the frame 1 with the heads A resting on the frame and the handles B extending therethrough. An axe is usually included as a part of the equipment 60 of a miner and as the head of the axe is large it is arranged within that portion of the frame 1 under the yoke 6 so that the handle B of this yoke can extend downwardly with the short side of the yoke 6 a cross bar 11 65 and the end of the frame as shown. Other tools such as picks C are arranged with their heads resting on the frame and their handles extending downwardly therethrough while the tongue 2 can be extended through the 70 eyes provided in the handles D and E of a saw and a shovel respectively. Small hammers can also be mounted on the tongue 2, the head F of one of these hammers being shown in 75 position and the handle G thereof being extended downwardly through the tongue. After the several tools have thus been assembled relative to the frame 1 and its tongue 2 the retaining strip formed of the yoke 6, strip 7 and finger 8 is swung to place with 80

the lug or ear 9 resting on the tongue. The shackle of a padlock 12 is then inserted through the registering openings 3 and 10 so that the parts of the protector are thus held together and it becomes impossible to remove or separate the several tools engaged thereby.

What is claimed is:

1. A protector of the class described including a member having an opening for the reception of the handles of certain tools, a tongue extending from one end of said member for insertion through the handles of other tools, a retaining member movably mounted relative to the handle engaging member, and means for holding the two members against relative movement, thereby to retain the tools against withdrawal of their handles from engagement with the member engaged thereby.

2. A protector of the class described including an elongated frame having a contracted portion at one end constituting a tongue, there being an opening through the member and extending longitudinally thereof, a retaining strip movably connected to one end of the frame, and means for detachably fastening the other end of said strip to the end of the tongue.

3. A protector of the class described including an elongated frame having a contracted portion at one end constituting a tongue, a retaining strip movably connected to one end of the frame, means for detachably fastening the other end of said strip to the end of the tongue, and means for separating the frame into separate spaces for the reception of the handles of tools.

4. A device of the class described including an elongated member for the reception of the handles of tools having heads adapted to rest on the member, a tongue at one end of said member for insertion through tools having eyes, a retaining member movably connected to the tool engaging member and movable to position to retain the tools in engagement with the member and the tongue thereon, and means for locking the members in tool retaining positions.

In testimony that we claim the foregoing as our own, we have hereto affixed our signatures.

LAWRENCE C. BURKS.
JOHN A. BUCHHEIT.
